DESIGN FOR A PENCIL

Edward J. Britton, St. Louis, Mo., assignor to St. Louis Pencil Company, St. Louis, Mo., a corporation of Missouri

Application July 16, 1935, Serial No. 57,672

Term of patent 7 years

To all whom it may concern:

Be it known that I, Edward J. Britton, a citizen of the United States and a resident of the city of St. Louis and State of Missouri, have invented a new, original, and ornamental Design for a Pencil, of which the following is a specification, reference being had to the accompanying drawing, forming part thereof.

I claim:

The ornamental design for a pencil substantially as shown.

EDWARD J. BRITTON.
